CLAIM

The ornamental design for a tape dispenser, as shown and described.

DESCRIPTION

FIG. 1 is a top, rear left perspective view of the tape dispenser according to the new design;

FIG. 2 is a bottom front left perspective view thereof;

FIG. 3 is a top plan view thereof;

FIG. 4 is a bottom plan view thereof;

FIG. 5 is a left elevation view thereof, the right elevation being a mirror image of the left elevation;

FIG. 6 is a front elevation view thereof; and,

FIG. 7 is a rear elevation view thereof.
